B. B. JONES ET AL

CHIN SUPPORT

Filed Nov. 30, 1923

FIG. 1.

Inventors

B. B. Jones.
E. O. Fields.

By

Lacy Tracy, Attorneys

UNITED STATES PATENT OFFICE.

BRINKLEY B. JONES AND ERIC O. FIELDS, OF MILAN, TENNESSEE.

CHIN SUPPORT.

Application filed November 30, 1923. Serial No. 677,836.

To all whom it may concern:

Be it known that we, BRINKLEY B. JONES and ERIC O. FIELDS, citizens of the United States, residing at Milan, in the county of

5 Gibson and State of Tennessee, have invented certain new and useful Improvements in Chin Supports, of which the following is a specification.

This invention is a device for supporting 10 the chain of a corpse while an embalmer is at work upon the same. The object of the invention is to provide a simple, light and inexpensive device by which the mouth of the corpse will be held closed notwithstanding 15 that the embalmer may find it necessary to shift the position of the body frequently while at work. The invention also seeks to provide a device for the stated purpose which, when not in use, will occupy but very 20 small space and may, therefore, be easily carried in a tool kit. The invention is illustrated in the accompanying drawing and will be hereinafter fully set forth.

In the drawing: 25 Figure 1 is a view in side elevation showing the device arranged for use, and

Fig. 2 is a plan view of the device showing it folded for placement in a kit.

In carrying out the invention, we employ 30 a frame bar 1 which is preferably of stout wire or light rod material bent into substantially U shape and to the center of this frame bar we secure a small arcuate plate 2 constituting a chin rest and adapted to be placed against the point of the chin when the device is applied. The chin rest may be secured upon the bar in any convenient manner, and we have illustrated a central post 3 fixed to the back of the chin rest 35 at the center of the same and through which the frame bar passes. Rigidity of location of the chin rest may be attained in any desired manner. Slidably and frictionally engaged upon the sides of the frame bar 1 are 40 carriers 4, and the ends of the frame bar are equipped with small knobs or other forms of stop 5 to prevent the said carriers being released from the frame bar. These carriers are bowed leaf springs having perforations 6 through which the sides of the frame bar pass, and it will be readily understood that the resiliency of the carriers causes the walls of the openings therein to bind yieldably upon the opposite sides of the frame bar so as to frictionally hold the carriers at any point of adjustment upon the

frame bars. Disposed between the sides of the frame bar and pivotally attached to the carriers at the centers of the same are head bands 7 and 8 which are resilient metal strips U-shaped, as shown clearly in Fig. 2, whereby they may be disposed over the head of the corpse and, when not in use, will fit closely within the U-shaped frame bar 1. These head bands are connected to the carriers by pivots 9 common to both bands but they have independent pivotal movement and one band is adapted to fit closely within the other so that there will be no interference with the relative pivotal movements. 60 65 70

When the device is not in use, it is folded, as shown in Fig. 2, and may then be placed within a small space in a tool kit. When the use of the device is necessary, the head bands are swung upon their pivotal mounting to project beyond the open side or end of the frame bar and pass over the head of the corpse, as clearly shown in Fig. 1. The chin rest 2 is brought against the chin of the corpse and the frame bar 1 is then adjusted slidably through the carriers 4 until the head is engaged sufficiently tightly to retain the device in its position. The resilient characteristics of the head bands permit them to readily accommodate themselves to any irregularities in the head formation so that the device will be firmly supported upon the head after it has been applied, and the slidable mounting of the carriers 4 upon the frame bar permits the said carriers to 80 85 90 95 100 be adjusted longitudinally of the frame bar so that the device may be easily adjusted to the length of the head. When applied, the device will support the chin so that the mouth will remain closed in all positions in which the head may be placed. The device is exceedingly simple and light and may be produced at a slight expense. It can be easily adjusted and will operate efficiently for the purpose for which it is designed. 105

Having thus described the invention, we claim:

1. A chin support for embalmers' use comprising a frame bar, a chin rest secured thereon, carriers slidably and frictionally engaged with the frame bar, and head bands pivotally mounted upon said carriers. 105

2. A chin support for embalmers' use comprising a U-shaped frame bar, a chin rest secured upon said bar at the center of the same, carriers slidably and frictionally mounted upon the sides of the frame bar, 110

and resilient head bands pivotally attached to the carriers and disposed between the same and between the sides of the frame bar.

3. A chin support for embalmers' use comprising a frame bar, a chin rest secured upon said bar at the center of the same, carriers consisting of bowed springs slidably engaged upon the sides of the frame bar, and

resilient head bands pivotally attached to the carriers and disposed between the same and the sides of the frame bar. 10

In testimony whereof we affix our signatures.

BRINKLEY B. JONES. [L. S.]
ERIC O. FIELDS. [L. S.]
